UNITED STATES PATENT OFFICE.

ROYAL W. JACKSON, OF QUINCY, ILLINOIS, ASSIGNOR TO GLENCO PRODUCTS COMPANY, OF QUINCY, ILLINOIS, A CORPORATION OF ILLINOIS.

HAND DUSTER.

Application filed June 4, 1927. Serial No. 196,437.

This invention relates to improvements in hand dusters or mops, and has for its principal object to provide a simple and economical device of the character indicated. 5 Other objects will appear from time to time as the description proceeds.

The invention further consists in a method of manufacture whereby the article may be produced at low cost. 10 The invention may best be understood by reference to the accompanying drawing which illustrates one form in which the invention may be embodied. In the drawings,

Figure 1 is a view showing one side of the hand duster, but with parts of the covering material omitted.

Figure 2 is a sectional view taken on line 2—2 of Figure 1.

Figure 3 is a sectional view on line 3—3 of Figure 1, showing the manner in which the 20 yarn may be applied.

In the embodiment illustrated, the hand duster comprises an envelope or body portion 10 made up of a continuous piece of fabric 11, or similar material and open at both ends. 25 In the preferred form shown, a single piece of fabric is used, with opposite terminal edges 22—22 sewed together along one side of the envelope. A plurality of rows 12—12 30 of long strands of yarn material are secured to the outer surface of the envelope, arranged so as to present a mop-like rubbing surface extending over the entire envelope. These rows are preferably arranged to extend continuously around the envelope, that 35 is to say, in a direction substantially parallel with the open end margins of the latter. Any suitable means of attaching the rows may be employed. For example, they may 40 be stitched on as shown. The envelope thus formed is by preference of ample proportions to accommodate the largest size hand. Means are provided for holding the envelope 45 and adjusting it to various sizes, as will now be described.

Intermediate the open ends of the envelope, and by preference substantially the middle thereof, I provide a plurality of connecting members 15—15 extending through the envelope at spaced intervals to form apertures for receiving the fingers of the hand.

In the form shown, four of such connecting members are shown to accommodate the fingers and thumb. The members 15—15 are effective to maintain the envelope in substantially flattened form, to readily receive the hand from either end or with the palm facing in either direction, the mop-like surface being such as to be effective in all positions of the hand just suggested. 55

In the preferred form illustrated, the connecting members 15—15 are formed of a single lacing member 14 suitably threaded through and about the envelope, and having free ends 16—16 extending in position to be 60 tied together for adjustment of the mop to various sized hands. The lacings preferably lie between two adjacent rows 12—12 of 65 yarn-like material arranged parallel thereto as has been described. Various means of 70 threading the lacing member may be employed, as for instance, the two center connecting members may be formed of a double loop, as shown. The lacing member may thus be adjusted by tightening or loosening 75 the ends 16—16 thereof, thereby changing as desired, the enclosed area of the central portion of the envelope in which the fingers are fitted, as is best shown in Figure 3.

Although I have described one specified 80 form in which my invention may be embodied, and a preferred method of manufacturing the same, it will be understood that many variations as to structure, materials, or methods of manufacture may be employed 85 without departing from the spirit and scope of my invention. Therefore, it should be understood that the invention is not limited to the illustrative form hereinbefore disclosed, excepting in so far as defined in the 90 following claims.

I claim as my invention:

1. As a new article of manufacture, a hand duster comprising an open ended envelope formed of a continuous piece of flexible material having rubbing material attached to opposite sides thereof, and a line of lacings connecting opposite sides of said envelope at a plurality of points across the central portion thereof to form openings for the fingers 100 of the hand.

2. As a new article of manufacture, a hand

duster comprising an open ended envelope formed of a continuous piece of flexible material having rows of strands of rubbing material extending in continuous lines about both sides of said envelope, and a line of lacing connecting opposite sides of said envelope across the central portion thereof and intermediate adjacent rows of strands of

rubbing material to form a plurality of openings for the fingers of the hand, said lacings being adjustable to afford different sizes of finger openings.

Signed at Quincy, Ill., this 31 day of May, 1927.

ROYAL W. JACKSON.
